UNITED STATES PATENT OFFICE.

CHARLES STANLEY RHOADS, JR., OF INDIANAPOLIS, INDIANA.

TELEPHONE SYSTEM.

1,324,746.

Specification of Letters Patent.

Patented Dec. 9, 1919.

Application filed June 28, 1917. Serial No. 177,437.

To all whom it may concern:

Be it known that I, CHARLES STANLEY RHOADS, Jr., a citizen of the United States, residing at Indianapolis, in the county of Marion and State of Indiana, have invented a certain new and useful Improvement in Telephone Systems, of which the following is a full, clear, concise, and exact description, reference being had to the accompanying drawings, forming a part of this specification.

My invention relates to telephone systems and more particularly to systems of the kind used for telephone train despatching in which a great many telephone substations are adapted for simultaneous connection to a single circuit. Circuits such as these may be all the way from one hundred to two hundred and fifty miles in length and in a great many cases are constructed of iron wire. This indicates the difficulties presented to the attempt to secure adequate transmission thereover.

In accordance with my invention I provide a receiver circuit at each substation having a very high resistance. In the preferred form of the invention I utilize a receiver having about fifteen hundred ohms of resistance, and this receiver I bridge directly across the line circuit. I have found that by using a receiver of this kind I am enabled to obtain satisfactory speech transmission over lines such as hereinbefore referred to.

I will describe one form which my invention may take more in detail by referring to the accompanying drawing illustrating a line circuit having various forms of substation circuits.

In this drawing I show a pair of line wires 1 and 2 as uniting substations A, B, C, D and E. I have shown at station A a transmitter 3 which together with the battery 4 and primary winding 5 forms the local circuit controlled by the switch lever 6. This switch lever 6 is conjointly operated with the switch lever 7, the switch lever 7 controlling the circuit through the secondary winding 8. The receiver 9 which is of fifteen hundred ohms resistance is connected directly across the line wires 1 and 2, having a condenser 10 in series in this bridge. The circuit including the secondary winding 8 and switch lever 7 is connected in bridge of the receiver 9. Thus for incoming transmission the switch levers 6 and 7 are not used to close their respective circuits. Thus the receiver

9 of fifteen hundred ohms resistance is alone in bridge of the line wires at this particular station.

With receivers of this resistance and with the circuit thus arranged I am enabled to carry on satisfactorily conversation over relatively poor line circuits even though a very large number of receiver bridges are permanently associated with the said line wires.

At station B I arrange the circuit including the secondary winding 8 and switch lever 7 so that it is adapted for connection to the line wires in a separate bridge, there being included in this separate bridge a condenser 11. The general plan however is of course the same as illustrated for the substation A.

At the substation C I show a structure similar to that indicated at substation A except that I insert an impedance coil 12 having a movable enveloping iron shell 13, which shell by its movement may increase or decrease the impedance offered by the coil 12.

At the substation D I place a receiver 9^a in a local secondary circuit by including it in series with a secondary 13, the primary 14 whereof occupies the position in the bridge circuit occupied by the receiver in the stations A and B.

At substation E I provide an auto-transformer coil 15 across all or part of whose turns the receiver 9^a is bridged, there being preferably included a coil 16 in circuit with said receiver.

At the substations D and E the coils 14 and 15 respectively provide the high resistance or impedance necessary, the receivers 9^a under those conditions being high or low wound as may best suit the requirements of the secondary circuit.

In using the words "high resistance" in the claim I mean a resistance of substantially fifteen hundred ohms, or thereabout.

From what has been thus described the nature of my invention will be clear to those skilled in the art.

What I claim as my invention is:

A long distance telephone transmission system having a plurality of substations all united by a common line circuit, each substation having a transmitter, a battery therefor, and a primary winding of an induction coil included in a local circuit, a high resistance receiver circuit including a receiver at each of said substations, said high resistance receiver circuit including an auto-

transformer together with a bridge about said auto-transformer including a receiver and a high resistance, connected in a bridge across said line circuit, a secondary winding 5 for the induction coil inductively associated with said primary winding and adapted for connection in bridge of said receiver, and manually operable means for conjointly con-

trolling the simultaneous closure and rupture of said local circuit and the circuit including said secondary winding.

In witness whereof, I hereunto subscribe my name this 12th day of May, A. D., 1917.

CHARLES STANLEY RHOADS, JR.

Witness:

H. F. STEVENSON.
